Primary Examiner—Catherine R Oliver(57) **CLAIM**

The ornamental design for a pill box, as shown and described.

DESCRIPTION

FIG. 1 is a top perspective view of a pill box of the present invention.

FIG. 2 is a bottom perspective view of the pill box of the present invention.

FIG. 3 is a front view of the pill box of the present invention.

FIG. 4 is a rear view of the pill box of the present invention.

FIG. 5 is a right end view of the pill box of the present invention.

FIG. 6 is a left end view of the pill box of the present invention; and,

FIG. 7 is an open perspective view of the pill box of the present invention.

The broken line showing of environment in the drawings is included for the purpose of illustrating only and forms no part of the claimed design.
